UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed December 9, 1922. Serial No. 605,793.

To all whom it may concern:

Be it known that I, HENRY W. O'NEILL, a citizen of the United States, residing at Brooklyn, in the county of Kings, State of New York, have invented certain new and useful Improvements in Telephone Systems, of which the following is a full, clear, concise, and exact description.

This invention relates to telephone systems and particularly to circuits employed in building up toll connections.

An object of this invention is to control a signal over a line circuit by the transmission of alternating currents over the line, alternating current of one character being automatically applied to the line when a cord circuit is connected to the line, and alternating current of another character being automatically applied to the line when the cord circuit is disconnected from the line.

Another object of the invention is to operate the signaling means at each end of a circuit in response to interruptions of the circuit at either end to apply alternating current to the circuit to actuate a signal at the distant end.

A feature of the invention resides in a plurality of cooperating relays which when operated to record a signal of one nature, are reset by the operation of a manual switch to record a signal of another nature.

The invention will be readily understood from the following detailed description and by reference to the accompanying drawings in which Fig. 1 shows a subscriber's line and equipment T of a toll line L terminating at an inward or switching operator's position C. Fig. 2 shows the equipment for the distant end of the toll line L terminating at an outward toll operator's position B together with such portions of a cord circuit K as are required for use with the toll line L.

It will be understood that in practice there may be a plurality of toll lines such as L extending between the distant offices for which a common order wire circuit (not shown) will be provided, whereby the outward operator at position B may request that connections be established by the operator at position C. It will also be understood that the operator at position B may have a plurality of cord circuits such as K at her position.

Assuming the operator at position B desires to establish a connection with the station A, she makes this request over an order wire circuit (not shown). The inward operator at position C may assign the toll line L and thereupon insert a plug 112 in jack 113 of the line at station A, while the outward toll operator at position B may insert plug 200 of the cord circuit K into jack 201.

Upon the insertion of plug 200 into jack 201, a circuit is established which may be traced from grounded battery, circuit controlling elements 202 and 203 associated with the acceleration type relays 204 and 205, respectively, normal contact of key 206, conductor 207, left-hand armature and back contact of relay 208, conductor 209, normal break contacts of relay 210, conductor 211, right-hand normal break contacts of relay 212, conductor 213, winding of relay 214, conductor 215, lamp 216, sleeve contacts of plug 200 and jack 201, conductor 217 and thence to ground through the winding of relay 218. If the plug 200 is inserted in jack 201 previous to the seizing of the line A by the operator at position C, lamp 216 lights in this circuit. It will appear later on in the description that as soon as plug 112 is inserted in jack 113, lamp 216 will be extinguished. Relay 218 in operating, connects the 1000-cycle current source 219 to the line conductors 220 and 221 whereupon current from this source flows out over the line. Relay 218, in attracting its lowermost armature establishes an energizing circuit for relay 222, which may be traced from grounded battery, lowermost armature and front contact of relay 218, conductor 223 to ground through the winding of relay 222. Relay 222 operates and disconnects the 1000-cycle current source 219 from the line conductors and connects the toll line conductors through to the tip and ring of jack 201. Relay 222 in operating also establishes an energizing circuit for relay 224 extending from grounded battery, lowermost armature and front contact of relay 222, conductor 225, and thence to ground through the winding of relay 224. Relay 224, in operating, does not affect the operation of the circuit in any way at this time as the conductors 226 and 227 leading from the 1500 cycle current source 228 are open at the back contacts of relay 218.

The current pulse from the 1000 cycle source 219, when applied to the toll line as previously mentioned, traverses a path extending from source 219, back contact and lower inner armature of relay 222, front contact and lower inner armature of relay 218, line conductor 221, lower armature and back contacts of relays 100 and 101, conductor 102, windings of the acceleration type relays 103, 104 and 105, conductor 106, back contact and upper armature of relay 100, line conductor 220, upper armature and front contact of relay 218 and back to the source 219 over the upper armature and back contact of relay 222.

The relays 103, 104 and 105 are respectively responsive to currents of 500, 1000 and 1500 cycle frequencies so that relay 104 is the only relay which operates in the circuit just traced. Relay 104 in operating, interrupts the normal energizing circuit for relay 107 which may be traced from grounded battery, circuit controlling element 108 associated with relay 104, conductor 109, winding of relay 107, and thence to ground through the front contact and armature of said relay 107. Relay 107 thereupon releases and prevents the illumination of lamp 110 at this time, assuming that the operator at position C has seized the line A.

At the instant the plug 112 was inserted into the jack 113, a circuit was established extending from grounded battery, winding of relay 114, winding of relay 111, sleeve contacts of plug 112 and jack 113, and thence to ground through the winding of cut-off relay 115. Relay 115 operates and disconnects the line relay 116 from the subscriber's line A. Relay 111, in attracting its right-hand armature places a momentary ground on conductor 117 to effect the momentary operation of relay 100 over an obvious circuit. The momentary ground placed on conductor 117 is sufficient to initially energize relay 123 over a circuit extending from grounded battery, circuit controlling element 121 of relay 103, conductor 122, upper winding of relay 123, normal break contacts of relay 123, conductor 124 to ground on conductor 117. Relay 100 in its momentary operation, connects the 500 cycle and 1500 cycle current sources 118 and 119 to the line conductors 220 and 221 whereupon a current pulse from the sources 118 and 119 flows out over the front contact and lower armature of relay 100, line conductor 221, lower inner armature and front contact of relay 218, lower inner armature and front contact of relay 222, ring contacts of jack 201 and plug 200, lower normal contacts of ringing key 229, conductor 230, windings of relays 204 and 205, conductor 231, upper normal contacts of key 229, tip contacts of plug 200 and jack 201, front contact and innermost armature of relay 222,

front contact and uppermost armature of relay 218, line conductor 220, upper armature and front contact of relay 100 and thence back to the current sources 119 and 118.

At the time that plug 200 was inserted in jack 201, relay 214 operated over the circuit previously traced. Relay 214, in operating, prepares a circuit for relay 210.

Relays 204 and 205 are responsive to 500 and 1500 cycle currents, respectively, from the sources 118 and 119, and upon the operation of relay 100, these relays energize, and at their controlling elements 202 and 203 remove battery 233, which heretofore shunted out relay 210. Upon the removal of this shunt, relay 210 operates over a circuit extending from grounded battery 232, left-hand normal break contacts of relay 212, winding of relay 210, armature and front contact of relay 214, winding of relay 214, conductor 215, lamp 216, sleeve contacts of plug 200 and jack 201, conductor 217 to ground through the winding of relay 218.

At the cessation of the impulse of double frequency currents, relays 204 and 205 restore current from battery 233 then flows out over a path extending from grounded battery 233, circuit controlling elements 202 and 203, normal contacts of key 206, conductor 207, armature and back contact of relay 208, conductor 209, front contact and armature of relay 210, conductor 234, winding of relay 212, sleeve contacts of plug 200 and jack 201, conductor 217 to ground through the winding of relay 218. Relay 212 operates in this circuit and removes battery 232 from the windings of relays 210 and 214 whereupon these relays are deenergized and lamp 216 extinguished. Relay 212, in operating locks over a path including its right-hand alternate contacts, conductor 211, normal contacts of relay 210 and the path previously traced to battery 233.

It will be noted that the contacts of relay 212 are of the make-before-break type, thereby insuring continuity of circuit during the operation of this relay.

The operator at position B on noting the darkening of lamp 216, realizes that the line A of the called party has been seized and she proceeds to ring the subscriber. In signaling the called subscriber, the operator actuates key 229 and in so doing, a circuit is established extending from one side of the 500 cycle current source 240, lower contacts of key 229, ring contacts of plug 200 and jack 201, front contacts and middle armatures of relays 222 and 218, line conductor 221, lower armatures and back contacts of relays 100 and 101, conductor 102, windings of relays 103, 104 and 105, conductor 106, back contact and upper armature of relay 100, line conductor 220, uppermost armature

tures and front contacts of relays 218 and 222, tip contacts of jack 201 and plug 200, upper alternate contacts of key 229 and back to the source 240.

- 5 The operation of key 229 also completes a circuit extending from grounded battery, conductor 250, lowermost contacts of key 229, conductor 251, winding of relay 208, sleeve contacts of plug 200 and jack 201, conductor 217 to ground through the winding of relay 218. Relay 208 energizes in this circuit and at its left-hand armature interrupts the energizing circuit for relay 212 which in turn, reestablishes the original 70 energizing circuit for relay 214 and lamp 216 with the exception that from conductor 207, the circuit passes over the armature and front contact of relay 208 instead of the armature and back contact as in the first 75 case. At its right-hand armature, relay 208 establishes an obvious locking circuit for itself. Lamp 216 thereupon relights upon the actuation of key 229.

80 Relay 103 being the only relay in the circuit previously traced including relays 103, 104 and 105, that is responsive to 500 cycle current, operates and at its circuit controlling element 121 interrupts the energizing circuit for relay 123. Relay 123, in retracting 85 its armature connects the ringing current source 125 to the ring conductor of the line and ground to the tip conductor so that current from source 125 traverses an obvious path over the subscriber's line loop to operate the bell at station A.

90 In response to this signal, the subscriber on line A removes the receiver from the switchhook thereby causing an increase of current through the lower winding of relay 123 which causes this relay to again energize and reestablish its locking circuit which extends from grounded battery, circuit controlling element 121, conductor 122, upper winding of relay 123, front contact 95 and middle armature of relay 123 to ground over the front contact and armature of relay 111. A circuit is thereupon established, which may be traced from grounded battery, winding of relay 127, resistance element 128, lower left-hand winding of repeating coil 129, front contact and lowermost armature of relay 123, lower armature and front contact of relay 114, ring contacts of plug 112 and pack 113, line loop and apparatus at 100 station A, tip contacts of jack 113 and plug 112, front contact and upper armature of relay 114, uppermost armature and front contact of relay 123, upper left-hand winding of repeating coil 129 to ground through resistance element 130. Relay 127 energizes in this circuit and establishes a circuit for relay 101 extending from grounded battery, front contact and armature of relay 127, conductor 131 to ground through the winding of relay 101. Relay 101, in operating, 105

110 at its lowermost contacts disconnects the relays 103, 104 and 105 from the line circuit and extends conductor 221 to the line side of the repeating coil 129, and at its upper contacts places a momentary ground on conductor 132 which momentarily completes an obvious circuit for relay 100.

115 Relay 100 in energizing, as in a previously described instance, effects the energization of relays 204 and 205 from the 500 and 1500 cycle current sources 118 and 119. As hereinbefore described, the operation of relays 204 and 205 again causes the operation of relays 210 and 212 and the deenergization of relay 214 and lamp 216. 120 Lamp 216 thereupon is extinguished to notify the toll operator at position B that the called party has responded and that the telephonic connection is completed and in 125 readiness for conversation.

130 Upon completion of the conversation, the called subscriber at station A replaces the receiver on the switchhook thereby interrupting the energizing circuit for relay 127 which in turn causes relay 101 to release. 135 Relay 101 in releasing, places a momentary ground on conductor 132 which momentarily operates relay 100 over an obvious circuit. Relay 100 in operating, again sends out an impulse of current from the sources 118 and 119 to cause the operation of relays 204 and 205 and subsequently to relight lamp 216 to notify the toll operator that the conversation has ceased.

140 The toll operator then removes plug 200 from jack 201 thereby causing the deenergization of relay 218 which in turn causes relays 222 and 224 to release. Before relay 224 releases, relay 218 will have deenergized thereby connecting the 1500 cycle current source 228 to the line conductors 220 and 221 over conductors 226 and 227 whereupon current from this source flows out over the line to actuate relay 105. Relay 105 in operating, interrupts at its circuit controlling 145 element 146, the normal energizing circuit for relay 145. Relay 145, in releasing, establishes a circuit for the initial energization of relay 107 extending from grounded battery, through the normal contacts 108 of relay 104, conductor 109, winding of relay 107, conductor 147 and contacts of relay 145 to ground. The response of relay 107 and the closure of its forward contacts substitutes ground potential to establish a self-locking 150 circuit for this relay independent of the ground through the contacts of relay 145. A circuit may now be traced from grounded battery, lamp 110, left-hand armature and front contact of relay 111 and front contacts of relay 107 to ground. The illumination of lamp 110 indicates to the operator at position C that the conversation has ceased 155 and the connection may be taken down whereupon she removes plug 112 from jack 160

113. Upon the removal of plug 112 from jack 113, cut-off relay 115 is deenergized thereby placing line relay 116 across the line A in readiness for a call originating at the station on line A. The removal of plug 112 from jack 113 also returns the toll line apparatus associated therewith to normal. The release of relay 111 opens the circuit for lamp 110 as traced through the front contact and armature of relay 107.

If, prior to the removal of plugs 200 and 112 from their respective jacks 201 and 113, and subsequent to the replacement of the receiver on the switchhook by the subscriber on line A, the calling subscriber should wish to be reconnected with the subscriber on line A, the operator at position B will again actuate key 229 and resignal the subscriber on line A as hereinbefore described.

20 The condenser 150, shown in Fig. 1, is connected in parallel with the winding of relay 100 and serves to prolong the impulse conveyed to relay 100 whenever relays 101 and 111 are operated. Upon the energization of 25 relay 101 or 111, ground is momentarily connected to the winding of relay 100 through conductor 132, whereupon relay 100 energizes for a short period and condenser 150 charges, so that upon removal of ground from conductor 132 to release relay 100 the condenser 150 discharges and sustains the pulse through the winding of relay 100.

The resistance elements 270 and 271, Fig. 2, are utilized to maintain relays 218, 222 35 and 224 operated during the successive operations of relays 212, 214 and 210.

It will be clear from the previous description that relay 111 is under the control of the operator at position C and that relay 107 40 is under the control of the operator at position B. With relay 111 deenergized and relay 107 energized (that is, in their normal conditions) the circuit for lamp 110 will be open. In case plug 112 should be inserted 45 into the jack of a line and no plug is inserted into jack 201 at the distant end of the toll line, the energized condition of relay 111 will cause the illumination of lamp 110; in a converse manner the insertion of plug 200 into jack 201 and the resulting release of 50 relay 107 while plug 112 is not connected to the line circuit, will also result in the lighting of lamp 110. Lamp 110 lighting in such a manner serves as a guard signal.

55 During the period of a connection the signal 216 may be flashed in case a party at station A may desire the attention of an operator. Responses of the relay 127 and in turn the relay 100 to a flashing movement 60 of the switchhook at station A will result in applications of current from the sources 118 and 119 to the line L to cause the relays 204 and 205 to establish respective cycles of response and release of the relays 214, 210 and 212 in such a manner that for each

"down" or disconnect position the lamp 216 will be lighted, while for each "up" or closed position of the switchhook the lamp will be extinguished.

During periods a connection may be established and while the receiver may be on its switchhook at the station A, the operator at "B" may, by removing and reinserting the plug 200 relative to the jack 201, cause the lamp 110 to be flashed. This is effected 75 by cycles of release and operation of the relays 218, 222 and 224 in applying impulses respectively from the sources 219 and 228 to alternately energize the distant relays 105 and 104. In response to such flashing, 80 the operator at C may connect the plug 112 to a supervisor's circuit (not shown) who may receive from the operator at B request for verification as to class of service or any other matter relative to the station or point 85 under call.

What is claimed is:

1. In a telephone system, first and second switching points, a line intermediate said points, a telephone station, a line intermediate said second switching point and said station, a signal at said second switching point, sources of alternating currents, means at said switching points for connection with said lines, and means responsive to the disconnection of said first means at said first point for selectively applying current from said sources to affect said signal. 95

2. In a telephone system, a first and a second operator's position, a line circuit joining said positions, a telephone station and a line therefor extending to said first position, switching means at said position joining said station to said second position, signaling means at said positions, sources of alternating currents, and means responsive to an interruption of a connection at either of said positions to apply current from one of said sources to affect the signal at the opposite position. 100

3. In a telephone system, a line circuit, a first and a second point joined by said line, a signal at said first point, a link circuit at said second point, sources of alternating currents, and means responsive to the connection of said link circuit to said line and responsive to the disconnection of said link circuit from said line to selectively apply current from said sources to actuate said signal. 115

4. In a telephone system, a line circuit, a first and a second operator's position joined by said line, a signal at said first position, a link circuit at said second position, sources of alternating currents, means responsive to the connection of said link circuit with said line, and responsive to the disconnection of said link circuit from said line to selectively apply current from said sources to said line, and means controlled by 125 130

said applied current for actuating said signal.

5. In a telephone system, a line circuit, a first and second operator's position joined by said line, a signal at said first operator's position, a link circuit at said second operator's position, sources of alternating currents, and means responsive to the connection of said link circuit with said line to 10 selectively apply the current from said sources to actuate said signal.

6. In a telephone system, a line circuit, a first and a second point joined by said line, a signal at said first point, sources of current, a link circuit associated with said line, and means responsive to the disconnection of said link circuit from said line to 15 selectively apply current from said sources to actuate said signal.

20 7. In a telephone system, a line circuit, a first and a second point joined by said line, a signal at said first point, a link circuit at said second point, sources of alternating currents, and means responsive to the connection of said link circuit to said line circuit to 25 connect current from one of said sources to said line to actuate said signal in one manner, and means responsive to the disconnection of said link circuit from said 30 line to connect current from another of said sources to said line to actuate said signal in another manner.

8. In a telephone system a line circuit, a cord circuit, sources of alternating currents, 35 switching means for selectively applying said sources to said line, a signal for said line, means for applying certain of said sources to affect said signal when the cord circuit is joined to the lines and for applying other of said sources to affect said signal 40 when the cord is removed from the line.

9. In a telephone system, a first, second and third point, circuits for interconnecting said points, switching means at said first 45 and second points for joining certain of said circuits in connecting said third point with said second point, a signal at said second

point, sources of alternating currents, and means responsive to the interruptions of the joined circuits at said first point to apply 50 said alternating currents in affecting the signal at said second point.

10. In a telephone system, a subscriber's line, a station thereon, an operator's cord circuit, a supervisory signal for said cord 55 circuit, a line circuit, a signal for said line circuit, sources of alternating currents, means responsive to the connection of said cord circuit to said line circuit for connecting one of said sources of current to said line circuit, means selectively responsive to currents applied to actuate said signal, means to connect said line with said subscriber's line, means for applying current to the subscriber's line to signal the station thereon, 60 means controlled by the called station for connecting certain of said current sources to said line circuit, and means controlled thereby to actuate said supervisory signal. 65

11. In a telephone system, a subscriber's line, a station thereon, an operator's cord circuit, a supervisory signal for said cord circuit, a line circuit, a signal for said line circuit, sources of alternating currents, means responsive to the connection of said cord circuit to said line circuit for connecting one of said sources of current to said line circuit, means at the distant end of said line 70 selectively responsive to currents applied to actuate said signal, means to connect said line with said subscriber's line, means for automatically applying ringing current to the subscriber's line to signal the station thereon, means controlled by the called station for connecting certain of said current 75 sources to said line circuit, and means controlled thereby to actuate said supervisory signal to indicate that the called party has disconnected. 80

In witness whereof, I hereunto subscribe 90 my name this 7th day of December A. D., 1922.

HENRY W. O'NEILL.
